CRANE BOOM ANGLE INDICATOR

Donald Behnk and Roger Protas, Pittsburgh, Pa., assignors
to S.I. Handling Systems, Inc., Easton, Pa., a corpora-
tion of Pennsylvania

Filed Dec. 8, 1969, Ser. No. 20,622

Term of patent 14 years

Int. Cl. D10—10

U.S. Cl. D52—6

FIG. 1 is a front elevation view of a crane boom angle indicator showing our new design;

FIG. 2 is a top plan view thereof;

FIG. 3 is a bottom plan view thereof;

FIG. 4 is a right side elevation view thereof on a smaller scale; and

FIG. 5 is a rear elevation view thereof.

The left side not shown in a mirror image of the right side shown in FIG. 4.

We claim:

The ornamental design for a crane boom angle indicator, substantially as shown and described.
